UNITED STATES PATENT OFFICE

GIUSEPPE F. PINSUTI, OF NEW YORK, N. Y.

BOTTLE STOPPER

Application filed January 12, 1928. Serial No. 246,113.

My present invention relates to a bottle stopper and more particularly to that type of bottle stopper which when fixed in place in the neck of a bottle is adapted to make the bottle non-refillable, which is to say that with the stopper in place the liquid contents thereof may be readily poured or shaken from the bottle but the bottle can not be refilled with a liquid of the same or a different nature than that which it originally contained.

This type of bottle stopper is particularly adapted for use at the present time with bottles containing cologne, toilet water, hair tonic, and various other similar liquids.

In carrying out the invention the stopper made in accordance therewith is so constructed as to include a body member having a shank adapted to fit into the neck of a bottle. The shank is fitted with a cup suitably connected thereto and forming a closure or casting for a valve device which permits the passage of the liquid from the bottle but prevents the passage of a liquid to the bottle. The structure may also include a means for locking the stopper in place in the neck of the bottle, all of which will be hereinafter more particularly described.

In the drawing Figure 1 is a central longitudinal section illustrating a bottle stopper made in accordance with this invention.

Figure 2 is a sectional plan on line 2—2, Fig. 1,

Figure 3 is an elevation and partial section showing the several parts of the stopper in the form thereof as illustrated in Figure 1,

Figure 4 is a view similar to Figure 1 showing another form of the invention,

Figure 5 is also a view similar to Figure 1 showing another form of the invention,

Figure 6 is a section on line 6—6, Figure 5,

Figure 7 is a central sectional elevation showing another form of the invention,

Figure 8 is a section on line 8—8 Figure 7, and

Figure 9 is also a central longitudinal section and partial elevation showing still another form of the invention.

Referring particularly to Figures 1, 2 and 3 it will be seen that in this form of the invention the stopper made in accordance there-

with is constructed to include a body member having a head 10 and a shank 11, the shank being of slightly smaller diameter than that of the head, these members with those associated therewith being insertable in the neck of a bottle, as indicated at 12. The peripheral portion of the head of the body member may be provided with flattened sides, as indicated at 13. While only two of these flattened sides are illustrated it will be understood that any desired number of them may be employed. Also in the peripheral portion of the head 10 there is a circumferential groove 14. In this form of the invention there are oppositely disposed grooves 15 and 16 in the walls of the shank 11 which extend into the head and terminate at the surface defining the groove 14, these grooves forming passages for the liquid to flow from the bottle when the stopper is in place in the neck thereof. At the inner end of the shank there is a recess 17 the purpose of which will hereinafter be more fully described.

Associated with the body member I employ a cup member 18. Although the body member is preferably made of porcelain and the cup member of a suitable metal it will be understood that these parts may be constructed of any material adapted to serve the purpose. In the bottom of the cup there is an opening or port 19 and the edge of the cup as indicated at 20, is preferably spun or otherwise inturned into a recess 21 provided for this purpose in the shank 11 in order that the cup may be swiveled to the shank. The cup is connected to the shank in such a manner as to provide a chamber therein which includes the recess 17 at the end of the shank. Within the cup there is a valve washer 22 made of sheet cork, rubber or similar material in which there is a centrally disposed opening or port preferably of the same diameter or configuration as that of the opening 19 in the bottom of the cup. The cup member also contains a valve 24 which in this form of the invention has a circular base adapted to bear against the valve washer 22 and extending from the base the other portion of the valve, as illustrated, is pyramidal having four sides at the edges of which there

may be suitable ribs. The pyramidal portion of the valve extends into the recess 17 at the inner end of the shank of the body member. The parts are so placed, however, that there is an appreciable play or longitudinal movement of the valve member to permit the liquid to flow freely when the valve member is unseated. Surrounding the shank of the body member there is a collar 25 which may be made of cork, rubber or any other suitable material and which is of slightly greater diameter than that of the body member whereby when forced into the neck of the bottle it engages the walls thereof with sufficient friction to make it impossible to remove the same. In this form of the invention, as clearly shown in Figure 1, the stopper as described is adapted to be forced in place in the neck of a bottle so that the outer surface of the head of the stopper is appreciably below the end of the neck of the bottle into which an ordinary cork of glass or other stopper 26 may be normally placed.

In the use of this stopper, as will now be apparent, when the bottle is tilted or inclined to pour the liquid therefrom the valve automatically leaves its seat and the liquid may flow through the ports 19 and 23 in the bottom of the cup and in the valve washer, and the spaces around the valve to the passages provided by the grooves 15 and 16, thence to the passage provided by the groove 14, and to the passages provided by the flattened sides of the head of the stopper. It will be clearly obvious that in attempts to refill the bottle either by pressure positive or negative, or otherwise, the valve will automatically return to its seat against the valve washer which in turn seats against the face or bottom of the cup, thereby preventing a liquid from flowing into the bottle.

By reference to Figure 4 it will be seen that the stopper may be so constructed that the cylindrical walls of the cup member are screw threaded, as indicated at 27, in which case, as will be understood, the surface of the bore of the neck of the bottle is similarly threaded, as indicated at 28 so that the collar is caused to engage between these screw threaded portions in securing the stopper in position. In this structure the edge of the cup is also spun into a circumferential groove provided therefor in the shank of the body member and adapted to have a slight longitudinal play on the body member. The shank in this instance is provided with a boss 29 so placed that when the head is engaged and turned in one direction by a suitable tool the boss engages the end of the screw thread 27 causing the cup to be turned with the head and the shank whereby the stopper may be turned to position causing the intervening portion of the collar to be engaged between the screw threads of the cup and the screw threads of the bore of the neck of the bottle

whereas when the head of the body member is turned in the opposite direction this boss 29 will clear and will not be engaged with the screw threads of the cup whereby while the stopper may be thus turned to place in the neck of the bottle it cannot be removed therefrom by a reverse operation.

It will be obvious that the particular form and construction of the valve member may be varied as well as the arrangement of the passages or ducts by which the liquid may enter the bottle. As shown in Figures 5 and 6 the body member of the stopper may be provided with a set of three grooves, 30, 31 and 32 in equally spaced positions and each forming a passage making communication between the chamber within the cup and the peripheral groove in the head of the body member. Also in this structure the valve member may be spherical, as indicated at 33, while the recess at the end of the shank may be formed to provide for a limited longitudinal movement of the valve.

By reference to Figures 7 and 8 it will also be apparent that the shank of the body member may be so constructed that the chamber therein is adapted to receive a cylindrical valve 34, the walls defining the chamber being curved as indicated at 25, and of any desired number so as to provide the necessary passages at the sides of the valve. In this structure there is a central passage 36 and lateral passage 37 making communication between the valve chamber and the peripheral groove in the head of the body member. In this instance the inner end of the valve member 34 may be made conical as indicated at 34'.

In the forms of the invention as hereinbefore described the stopper is so constructed that in its entirety it is adapted to lie within the neck of the bottle. By reference to Figure 9, however, it will be obvious that the stopper may be so formed that a portion thereof lies within the neck of the bottle and a portion thereof extends beyond the same. In this structure the head 38 of the body member is provided with a flange 39 adapted to contact with the end of the neck of a bottle and the body member also includes a stem extending upwardly therefrom and adapted to receive a cap or cover 41. In this structure there is a centrally disposed bore or passage 42 extending through the stem and the body member making communication with the valve chamber at the inner end of the shank of the body member. The valve chamber in this structure is indicated at 43 and, as illustrated, the valve 44 is spherical as in the structure shown in Figures 5 and 6 although, as will be understood, it may be of any other suitable configuration. In this form of the device the face of the bore of the neck of the bottle is threaded, as indicated at 45 while correspondingly the cylindrical wall of the

cup 46 is threaded, as indicated at 47. The edge of the cup, as hereinbefore described, is also turned into a recess provided for this purpose in the shank of the body member, as indicated at 48 and the shank is formed with a boss 49 in a manner similar to that shown in Figure 4 whereby the stopper may be turned in one direction and the boss caused to engage with the end of the screw thread of the cup to force the stopper to place with the flange 39 bearing against the end of the neck of the bottle and the collar of rubber or cork intervening between the screw threads on the neck and those on the cup whereby when the body member is turned in the opposite direction the boss does not engage the screw thread so that by turning the body member in the opposite direction it merely swivels on the cup member and thereby the stopper is locked in position in the neck of the bottle. As in other forms of the invention in this case there is a valve washer 50 having an opening or port 51 therein corresponding in area with the port 52 in the end of the cup member. In all instances, as illustrated, the diameter of the valve washer is slightly less than the inner diameter of the cup member in order to obviate any possibility of the valve washer wedging and thus interfering with the operation of the stopper. It will also be understood that the stopper device may be inserted to any desired extent in the neck of the bottle. In some instances the outer face of the stopper may be flush or substantially flush with the end of the neck of the bottle and the neck provided with lugs 53 for receiving and maintaining the usual cap thereon and in any event the outer surface of the body member of the stopper may be provided with suitable recesses, for example as indicated at 54, for receiving a tool by means of which the stopper may be turned to place in the neck of the bottle. Obviously also the locking device, as hereinbefore described, is the equivalent of a ratchet, any form of which may be employed whereby when the body of the stopper is turned in one direction it will carry the cup member with it whereas when turned in the opposite direction the cup after having been seated will remain in place. Still furthermore it will be apparent that in some instances particularly in a structure in which the walls of the cup are not threaded and the stopper is inserted an appreciable distance in the neck of the bottle, for example, as illustrated in Figure 1, the cup member may be secured rigidly to the shank of the body member by having a portion thereof indented into one or both of the grooves forming the longitudinal passages or into a separate groove provided for this purpose.

I claim as my invention:

1. In a bottle stopper, a body member having a head and a shank, a cup having the screw thread formed therein and being con-

nected on the said shank to turn thereon, there being a chamber within the cup between the same and the end of the shank, a valve movable in the said chamber, the cup having a port in the base thereof and the body member, a passage therein for the flow of the liquid, and means carried by the shank co-operating with the cup for turning the cup by the shank when the shank is turned in one direction and permitting the cup to remain stationary when the shank is turned in the opposite direction.

2. In a bottle stopper, a body member having a head and a shank, a cup having a port in the base thereof, screw threads in the walls thereof and its edge turned into a recess in the shank to be swiveled thereon, there being a chamber in the cup and between the same and the end of the shank, a valve movable in the chamber, there being a passage in the body member for the flow of the liquid, and means carried by the shank and adapted to engage a portion of the screw thread of the cup to turn the same with the shank when the latter is turned in one direction and to permit the cup to remain stationary when the shank is moved in the opposite direction.

3. In a bottle stopper, a body member having a head and a shank, a cup having a port in the base thereof, screw threads in the walls thereof and its edge turned in to a recess in the shank to be swiveled thereon, there being a chamber in the cup and between the same and the end of the shank, a valve movable in the chamber, there being a passage in the body member for the flow of the liquid, and a boss on the said shank positioned to engage a portion of the screw threaded walls of the cup when the shank is turned in one direction to cause the cup to move therewith and to permit the cup to remain stationary when the shank is turned in the opposite direction.

4. In a bottle stopper, a solid body member having a head adapted to fit the neck of a bottle and a shank of smaller diameter extending therefrom, the said shank having a recess forming a passage in the face thereof and extending from the inner end of the shank to the said head, a cup connected to the said shank and extending appreciably below the same to provide a chamber within the cup and between the same and the end of the shank, and a valve within the said chamber adapted to bear against the face of the cup and to be limited in its movement between the same and the end of the shank, there being a valve port in the base of the said cup.

5. In a bottle stopper, a solid body member having a head adapted to fit the neck of the bottle and an integral shank extending therefrom and of smaller diameter, the outer face of the head being conical and the surface of the shank being provided with a longitudinal groove forming a passage extending from the head to the end of the shank, a cup connected

to and extending from the said shank and forming a valve chamber therein which extends from the base of the cup to the base of the shank, the base of the cup being provided with a valve port, and a valve within the said chamber adapted to seat against the base of the cup and to be limited in its movement between the same and the end of the shank.

6. In a bottle stopper, a solid body member having a head adapted to fit the neck of a bottle and an integral shank of smaller diameter extending therefrom, the peripheral portion of the head being provided with a flattened face and the surface of the shank with a groove forming a longitudinal passage extending from the head to the end of the shank, a cup connected to and extending from the shank to provide a chamber within the cup and between the end of the shank, the base of the cup having a valve port therein, a valve washer within the cup, the said valve washer having a port therein, and a valve lying within the cup and adapted to seat against the said valve washer and limited in its movement between the same and the end of the said shank.

7. In a bottle stopper, a body member having a head adapted to fit the neck of the bottle and an integral shank extending therefrom and of smaller diameter, the surface of the shank being provided with a longitudinal groove forming a passage extending from the head to the end of the shank, a cup connected to the said shank and forming a valve chamber therein, the said chamber communicating with the longitudinal groove at the end of the shank, the base of the cup being provided with a valve port, and a valve within the said chamber adapted to rest against the base of the cup and be limited in its movement between the same and the end of the shank.

8. In a bottle stopper, a body member having a head adapted to fit the neck of the bottle and an integral shank extending therefrom and of smaller diameter, the surface of the shank being provided with a longitudinal groove forming a passage extending from the head to the end of the shank, a cup connected to the said shank and forming a valve chamber therein which extends from the base of the cup to the base of the shank, the base of the cup being provided with a valve port, and a valve within the said chamber of smaller diameter than the cup thereby facilitating the passage of liquid to the longitudinal groove when the same is positioned against the end of the shank.

Signed by me this 9th day of January,
1928.

GIUSEPPE F. PINSUTI,
